UNITED STATES PATENT OFFICE.

FREDERICK G. NORTON, OF CHICAGO, ILLINOIS, ASSIGNOR TO THE NORTON ELECTRICAL MANUFACTURING COMPANY, A CORPORATION OF NEW JERSEY.

MACHINE FOR PRESSING CLOTHING.

No. 811,241.

Specification of Letters Patent.

Patented Jan. 30, 1906.

Application filed September 19, 1904. Serial No. 224,941.

To all whom it may concern:

Be it known that I, FREDERICK G. NORTON, a citizen of the United States, residing in Chicago, in the county of Cook and State of Illinois, have invented a new and useful Improvement in Machines for Pressing Clothing, of which the following is a specification.

This invention relates to the construction of ironing-machines used in clothing manu-
factories for pressing or smoothing seams, edges, and other parts of clothing.

I have heretofore constructed machines employing electricity as the means of creating the pressure by the iron upon the garment, the iron being drawn directly down upon the cloth by a powerful magnet or magnets located below the ironing-board and the lines of force passing through the board and also through the cloth being ironed. In this construction there is much loss of power, and my principal endeavor in the present invention has been to avoid this loss, so that the machine can be efficiently operated by the use of an electric current much less than that required in the machine above referred to, and also to obtain a construction permitting the shifting of the electric power devices with the shifting of the iron.

The invention consists in the novel construction hereinafter described.

In the accompanying drawings, forming a part of this specification, Figure 1 is a front elevation of my invention. Fig. 2 is a section on the line 2-2 of Fig. 1. Fig. 3 is a partial plan. Fig. 4 is a detail vertical section of the joint in the frame transmitting power from the magnets to the iron, and Fig. 5 shows the manner of wiring the machine.

Referring to said drawings, 6 represents the ironing or garment-supporting board mounted upon standards 7, 7, and 8 is the iron. While the iron is electrically operated so far as the exertion of pressure upon the seam is concerned, the electric currents do not pass through the table or garment, nor do they reach the iron itself, as in the prior machines mentioned by me, but, instead, the electrically-operating devices are preferably all located under the table and are connected to the iron by a U-shaped frame which may or may not embody adjustable joints. In the preferred construction this frame con-

sists of a ribbed casting 9, joined to the magnets at one end and to an arm 10 at the other end, and a slideable bar 11, moving through a sleeve formed upon the arm 10 and connecting the frame to the iron. The iron is provided with the usual handle 12, mounted upon a stem 13, extending downward through the forked end of the arm 11 into the iron. The stem is confined in the forked end of arm 11 by a pin 14, and a spring 15 encircles the stem 13 between the handle and the forked arm. With this construction the iron is free to be turned about the axis of the stem 13, so that its point will look in any desired direction, and the downward pressure upon it from the handle is rendered elastic, the stem being compressible in the iron in the usual manner. The arm 11 is provided with a cross-pin 16, adapted to prevent it from moving too far in one direction.

The joint between the arm 10 and the casting 9 is clearly shown at Fig. 4. The arm 10 is keyed to a vertical pivot 17 by the pin 18. This vertical pivot extends downward into a recess formed in the casting 9 and is movable in such recess. A spring 40 is inserted between the bottom of the recess and the pivot, and at its upper end the pivot is hollowed out and receives the pointed end of an adjusting-screw 19, operated by a hand-wheel 20. The end of the arm 10 enters the slot 21 formed in the casting, and an open space 22 above and below the end of the arm is provided to permit vertical adjustment of the arm through the medium of the screw 19. When the screw is turned down, the spring 40 yields and the arm is carried downward in the slot 21, and when the screw is withdrawn the spring 40 expands and forces the arm upward. This adjustment is employed when a change of thickness of the garments being ironed occurs; but the construction is such that no perceptible vertical play is permitted to the iron, so that the joint is adapted to transmit to the iron the full force received by the casting 9 from the electrical devices, as now to be described. The frame 9 carries at its lower end two power depending magnets 23 and, together with such magnets, is supported from two rods 24-24, supported in the standards 7 and having length sufficient to enable the iron to be used at any point in the length of

the table. The frame and magnets are movable freely along these rods, being supported thereon by rollers 25 and hangers 26, attached to risers 27 on the end of the casting 9. There are two rollers and two hangers on each of the rods, and the hangers upon each side may be united by braces 28, if desired. The rods are supported in bearings 29, which rest upon springs 30 and have a slight vertical movement, and the rods are insulated from the bearings by insulation 31. I also employ insulation 32 between the hangers 26 and the risers 27. The manner of wiring the magnets will be understood from Fig. 5, and the circuit is closed whenever it is desired to cause the magnets to operate in any suitable way—as, for instance, by means of a foot-treadle 33. Below the magnets and supported in the standard 7 is a stationary armature 34, adapted to act with the magnets in any position to which they may be carried.

With this construction the operation will be substantially as follows: Supposing the garment to be pressed is in position upon the table and that the iron is in position upon the garment, the operator by means of the circuit-breaker treadle 33 or other suitable means closes the circuit and energizes the magnets. The magnets will now be attracted by the armature and drawn down thereto, and in such movement the pressure created is transmitted by the frame 9, 10, and 11 to the iron. The pressure thus caused by the iron will depend, of course, upon the strength of the current employed and may be made as great as the work to be done requires. In traveling along the garment the operator moves not only the iron, but at intervals he moves the power-transmitting frame also, the current acting in the same manner in all positions of the magnets relative to the armature and causing the same pressure in all positions. The frame is provided with a lug 35 upon the casting 9 and a second lug 36 on the arm 10, adapted to engage each other and insure this traveling by the frame when the iron is moved in one direction. When the iron is moved back, the arm 10 swings on the pivot 17; but by means of the lugs 35 and 36 the operator insures the main positioning movements of the frame and power devices. By commencing, therefore, at one end of the garment the operator insures the movement of the magnets and power-transmitting frame in conformity with the movements of the iron as the pressing proceeds without any labor or thought upon his part. At the same time the iron may be stopped in its forward movement and turned back in order to go over portions which do not yield readily to the iron.

It will be noted that the entire electromotive force is exerted directly between the magnets and armature without being compelled to pass through the table or the gar-

ment under operation, so that there is no loss of current, and also that I dispense with the levers and fulcrums heretofore used in mechanically-operated machines—such, for instance, as those shown in the patent to Varney, No. 322,217.

I claim—

1. The combination with the table and the iron, of a magnet and armature for depressing the iron, such magnet and armature being located in close proximity to each other and upon the same side of the table, and a rigid connection for transmitting power to the iron.

2. The combination with the table and the iron, of a magnet and armature for giving pressing power to the iron, such magnet and armature being located in close proximity to each other, and below the table, and a rigid connection for transmitting power to the iron.

3. The combination with the table and the iron, an electromagnet and armature, one of which is movable relative to the other and connected to the iron by a rigid connection so that the iron is depressed whenever the magnet is energized.

4. The combination with the table and the iron, of an electromagnet and armature, one of which is movable relative to the other and both of which are located below the table, and a rigid connection between the iron and the moving one of said electric parts, whereby the iron is depressed by the direct action of the electromotive force.

5. The combination in a seam-pressing machine, of an iron, a table along which the iron is movable, electromotive power mechanism movable with the iron, and a rigid connection between said mechanism and the iron, the mechanism depressing the connection and thereby depressing the iron.

6. The seam-pressing machine wherein are combined an iron, a rigid frame joined to the iron, and an electromagnet exerting a direct pull upon the frame and thereby causing the desired pressure by the iron and the armature coacting with said magnet.

7. In a seam-pressing machine, the combination of an electrically-depressed iron and its electric operating means, the latter being arranged wholly at one side of the table so that the lines of force do not pass through the table or cloth and a connection between said electric operating means and the iron.

8. In a seam-pressing machine, the combination of an electrically-depressed iron, and electric means for depressing the same, the iron forming no part of said depressing means but being mechanically connected thereto.

9. The combination with the stationary table and iron movable lengthwise of the table, of electric power devices movable along the table with the iron and causing the pressure by the iron, and a connection between the

iron and said power devices, the latter traveling with the iron and embodying a pivotal joint permitting some movement by the iron independent of the power devices.

- 5 10. The combination with the table and iron, of electric power devices movable along the table with the iron and causing the pressure by the iron, and a connection between the iron and said power devices and traveling with them, said connection embodying a pivotal joint provided with engaging lugs for insuring the movement of the connection with the iron when the latter is moved in one direction.
- 15 11. The combination with the table and iron, of electric power devices movable along the table with the iron and causing the pressure by the iron, and a connection between the iron and said power devices and traveling

with them, said connection embodying a joint 20 permitting vertical adjustment of the iron.

12. The combination with the table and the iron, of a depressible magnet movable with the iron along the table, an armature made long enough to serve the magnet in any 25 position of the latter, and a frame connecting the magnet to the iron.

13. The combination with the table and the iron of a depressible magnet movable along the table, ways upon which the magnet 30 moves and is supported, an armature capable of serving the magnet in all its different positions, and a rigid movable frame connecting the magnet to the iron.

FREDERICK G. NORTON.
